UNITED STATES PATENT OFFICE

95,506

DESIGN FOR A BOTTLE

William Guyer, New York, N. Y., assignor to Joseph E. Seagram & Sons, Inc., Lawrenceburg, Ind., a corporation of Indiana

Application February 27, 1935, Serial No. 55,643

Term of patent 14 years

To whom it may concern:

Be it known that I, William Guyer, a citizen of the United States, residing at New York, county of New York, and State of New York, have invented a new, original, and ornamental Design for a Bottle, of which the following is a specification, reference being had to the accompanying drawing forming a part thereof.

I claim:

The ornamental design for a bottle as shown.

WILLIAM GUYER.
